KNEE BRACE

David M. Bullock, Urbana, Ill., assignor to Rawlings Manufacturing Company, St. Louis, Mo., a corporation of Missouri

Application July 27, 1938, Serial No. 221,490

5 Claims. (Cl. 128—88)

This invention relates to a novel knee brace that is adapted to be used principally by athletes to protect an injured knee joint and cause the joint to function properly, without subjecting the user to pain or discomfiture. While the device is designed primarily for use by an athlete who has a so-called "bad knee", it is well adapted for use as a protecting device for a normal knee joint, inasmuch as it comprises a protecting member that embraces and extends over the knee joint and its surrounding structure, and also a means that forms, in effect, an artificial tendon that produces proper reflexes in the user's leg and insures proper functioning of the co-acting parts of the knee joint if the knee joint is subjected to a shock or blow when the device is in use.

The bony structure of the knee joint, being shallow, the articulation of the femur and tibia is held firmly together by what is known as capsule ligaments and also by internal crucial ligaments. These ligaments add support and steadiness to the joint. Numerous tendons also pass down on the medial and lateral sides of the joint and have their insertion well below the knee joint. There is also encased in the anterior or patella ligament a part known as the patella or knee cap, which has its insertion on the tibia. Between the bones is found what is known as a semi-lunar cartilage, which is a washer-like pad of a very brittle nature.

Due to its peculiar construction, the knee joint and its surrounding structure are very easily injured. One form of injury that is common, particularly among athletes, is over-extension of the knee joint, caused by a blow on either side of the knee joint when the user's foot is fixed or stationary and the user's body is forced into a twisting position, resulting in straining or rupturing of the capsule ligaments. The change in the condition of the capsule ligaments imposed considerable pressure upon the semi-lunar cartilage and the crucial ligaments, and if an injured knee joint is not mobilized for a proper period of time sufficient to allow normal healing, it is liable to become elongated. If this occurs, there will be too much free movement of the free joint, with the result that the cartilage is apt to become ruptured. After the cartilage has become ruptured or broken, it will never unite, and the only way the joint can be corrected is by an operation. If the cartilage is broken, the bending of the knee is liable to dislodge the cartilage or force it out of position between the parts of the knee structure with which it co-

acts, and when this occurs, the individual suffers great pain.

The main object of my invention is to provide a knee brace which is of such construction and design that when it is arranged in operative position on the user's leg, it will effectively support weakened ligaments and also maintain sufficient pressure on the knee joint in the zone where the cartilages are located, to eliminate the possibility of the semi-lunar cartilage slipping or becoming displaced.

Another object is to provide a device, which, when applied to an injured knee joint, will insure the joint functioning properly, and will permit the user to walk, run, kneel, or arise, without being subjected to pain or discomfiture.

Another object is to provide a device, which, in addition to having the desirable characteristics above described, is of such construction that it affords adequate protection to the knee proper and covers the bursa that are located in the front part of the knee proper, above and below the joint.

Another object is to provide a knee brace of the kind above described, that can be easily modified or adjusted to vary the pressure exerted by same on the knee joint and its surrounding structure.

And still another object of my invention is to provide a knee joint brace and protecting device that is equipped with an artificial tendon means which produces proper reflexes in the user's leg, if the tendons and ligaments of the user's knee joint fail to function properly when the device is in use.

To this end I have devised a knee brace, which, in its simplest form, comprises or is composed of a means that constantly exerts a yielding pressure on the femur and tibia of the knee joint in such a way as to maintain pressure at all times over the area of the knee joint where the cartilages are located. Said means may be constructed in various ways without departing from the spirit of my invention, but in the preferred form of my invention herein illustrated it consists of an elastic cord that exerts pressure on the co-acting parts of the user's knee joint in a direction tending to securely hold the semi-lunar cartilage between the parts with which it co-acts and also produce proper reflexes between the femur and tibia, in the event the capsule ligaments and/or the crucial ligaments are weak or incapable of performing their normal function. In addition to the means above referred to, my improved knee brace also prefer-

ably comprises a protecting member constructed so as to embrace or cover the knee proper and the bursa that are located in the front part of the knee structure above and below the joint, 5 the said means and protecting member being combined in such a way that the device as an entirety is securely held in operative position on the user's knee with the protecting member embracing and pressed firmly against the side 10 portions of the knee joint structure. If desired, the device may comprise a pair of jointed metal side braces disposed so as to give support to the knee in general and aid in maintaining the proper position of the device on the user's knee and leg, but said jointed metal braces are not absolutely essential to the successful operation of my improved knee brace, although I prefer to construct the device in the particular manner herein illustrated, as I have found that such a device makes it possible for a person who has a "bad knee" to play football, or basket ball, with perfect safety and comfort.

Figure 1 of the accompanying drawing is a front elevational view of my improved knee brace, 25 arranged in operative position on the user's leg.

Figure 2 is a side elevational view of said knee brace; and

Figure 3 is a rear elevational view of said knee brace.

30 In the drawing A designates any type or kind of a means, which, when positioned upon the user's leg, will exert pressure on the femur and tibia of the knee joint in a direction to assist or augment the action of the knee joint ligaments and maintain pressure at all times over the area 35 of the knee structure where cartilages are located. Preferably said means A consists of an elastic cord disposed so as to assist in the reflex actions of the user's leg and maintain the semi-lunar 40 cartilage in proper position, even though the capsule ligaments and the crucial ligaments have been strained to such an extent as to produce what is commonly referred to as an over-extension of the knee joint. As previously stated, the 45 particular form or construction of the means A is immaterial, so long as it is of such design that it will form, in effect, an artificial tendon means that maintains or tends to maintain the co-acting parts of the knee joint structure in their proper 50 positions and cause or assist said parts to function properly when the user is walking, running, kneeling, or arising.

As shown in the drawing, the elastic cord A that constitutes the artificial tendon means of 55 my improved knee brace extends across the rear side of the lower portion of the user's leg at a point below the knee (see Figures 2 and 3), and then leads upwardly and forwardly to a protecting member B that is positioned over the knee, 60 as shown more clearly in Figures 1 and 2, the elastic cord A extending upwardly over the side portions of the protecting member B, and thence rearwardly to an anchoring device located on the 65 rear side of the user's leg at a point above the knee. The cord A has sufficient tension to maintain the semi-lunar cartilage of the knee joint in proper position at all times, irrespective of the condition of the ligaments of the knee structure, 70 and also exert a constant forward thrust on the lower portion of the user's leg, with the result that it assists in the proper reflex actions of the leg. The elastic cord A, in addition to acting as an 75 artificial tendon means, also serves as a retaining means or holding means for the protecting

member B that insures said member remaining in proper position on the user's knee joint.

Usually, the protecting member B will be constructed in the form of a pad of such shape and size that it will extend laterally over the side 5 portions of the knee, and also extend upwardly and downwardly from the knee joint, so as to cover the bursa that are located at the front part of the knee structure above and below the joint. I prefer to make said pad B from leather or some 10 other suitable flexible material, and form an opening x at the center of same, as shown in Figure 1, so as to allow free movement and sliding of the patella or knee cap. The protecting member B is provided with loops 1 and 2 that serve 15 as guides for the elastic cord A, and the loops or guides 2 that are located at the center of the protecting member are arranged in slightly offset relationship with the guides or loops 1, so as to insure that the central side portions of the protecting member B will be pressed inwardly into snug engagement with the sides of the knee joint structure, the central portion of said protecting member being of slightly greater width than the top and bottom portions of said member, as illustrated in Figures 1 and 2.

In order to facilitate proper installation of the two parts A and B, above described, I prefer to equip my improved knee brace with an elastic supporting member C of tubular form in general 30 outline that is adapted to be drawn upwardly over the user's leg and arranged in approximately the position shown in the drawing, said supporting member C being of such shape and dimensions that it will snugly embrace the portion of the 35 user's leg in the zone of the knee joint. The supporting member C has combined with same two pairs of jointed metal braces disposed at the opposite sides of said supporting member and arranged so that they give support to the knee in 40 general, but do not interfere with the natural movements of the user's leg and knee joint. Usually, each of said metal braces will be constructed from two pieces of steel or other suitable material 45 3 having their inner ends joined together by a hinge or pivot 4 and arranged inside of a leather casing 5 that is sewed to the supporting member C, as shown in Figure 2. Said jointed braces extend longitudinally of the supporting member C at the opposite sides of same, and each of said 50 braces is provided adjacent its upper and lower ends with loops or guides 6 through which the tension member or elastic cord A extends. Attached to the rear side of the supporting member C adjacent the upper end of same is an anchoring device 7 of any preferred form or construction, that is used to secure the free ends of the 55 elastic cord A. As previously stated, the cord A extends transversely across the lower portion of the user's leg at a point below the knee cap, and in order to prevent said cord from cutting into 60 the leg and causing discomfort to the user, I arrange a piece of leather or other suitable material 8 at the rear side of the supporting member C, adjacent the lower end of same, so as to 65 form a bearing piece for the elastic cord A that is of sufficient area to prevent said cord from cutting into the user's leg.

To install my improved knee brace the user draws the supporting member C upwardly over 70 the leg into the position shown in Figure 2. The protecting member B is then arranged over the knee cap, after which the elastic cord A is disposed transversely across the rear side of the lower portion of the leg and then drawn up- 75

wardly through the guides 6 at the lower end of the jointed metal side braces and the guides 1 and 2 on the protecting member B, the free ends of said elastic cords A being passed rearwardly 5 through the guides 6 at the upper ends of the jointed side braces and then attached in any suitable way to the anchoring device 7 located at the rear side of the upper end of the supporting member C. In installing the device the elastic 10 cord A is drawn tightly enough or is placed under sufficient tension to insure that it will function in the way previously explained, and hold the protecting member B in snug engagement with and in proper position upon the knee joint. 15 The free ends of the elastic cord A may either be passed through loops on the anchoring device 7 and then knotted, or the anchoring device may be equipped with holding devices 7^a for the cord A, constructed in such a way as to facilitate the 20 adjustment of said cord or the disconnection of same from the anchoring device.

Having thus described my invention, what I claim as new and desire to secure by Letters Patent is:

- 25 1. A knee brace, comprising a protecting member adapted to be mounted on the user's knee and having provision for allowing free movement and sliding of the knee cap, elastic strands disposed longitudinally of said protecting member 30 and extending rearwardly from the upper and lower ends of same, and means for maintaining said strands under tension and anchoring them to the user's leg at points above and below the knee.
- 35 2. A knee protecting device, comprising an elastic supporting member adapted to be mounted on the user's leg in the zone of the knee joint, a protecting member positioned on said supporting member and constructed so as to embrace the 40 side portions of the user's knee joint and protect the bursa above and below the joint when the device is in operative position, elastic strands extending longitudinally of said protecting member in guides thereon and also extending rearwardly from the upper and lower ends of said 45 protecting member, and means for holding said

strands under tension and anchoring said strands to said elastic supporting member.

3. A knee protecting device, comprising a protecting member constructed so as to embrace the side portions of the user's knee joint and protect the bursa above and below the joint, jointed braces arranged at opposite sides of the knee and disposed longitudinally of the user's leg, and elastic strands extending longitudinally of said protecting member in guides thereon and also 10 extending rearwardly from said protecting member through guides in the end portions of said jointed braces.

4. A knee protecting device of the kind described in claim 3, in which said strands are 15 joined together at their lower ends by a portion which extends transversely across the rear side of the user's leg at a point below the knee joint, when the device is arranged in operative position on the user's leg the upper ends of said strands 20 being adapted to be attached to anchoring devices located adjacent the rear side of the user's leg above the knee joint.

5. A knee protecting device, comprising an elastic supporting member adapted to be mounted 25 on the user's leg in the zone of the knee joint, jointed side braces combined with said supporting member and arranged so that when said supporting member is in operative position, said braces are located at the opposite sides of the 30 user's knee joint, a protecting member positioned at the front side of said supporting member, and constructed so as to embrace the side portions of the user's knee joint and protect the bursa above and below the joint, an elastic cord 35 extending across the rear side of said supporting member at a point below the user's knee joint and comprising extensions or strands which lead forwardly from the lower ends of said jointed braces, thence upwardly through guides on said 40 protecting member and thence rearwardly through guides on the upper end portions of said braces, and anchoring devices on said supporting member located at the rear of said side braces for securing the free ends of said strands.

DAVID M. BULLOCK.
